UNITED STATES PATENT OFFICE.

JESSE A. B. SMITH, OF STAMFORD, CONNECTICUT, ASSIGNOR TO UNDERWOOD TYPE-WRITER COMPANY, OF NEW YORK, N. Y., A CORPORATION OF DELAWARE.

BILL FORM.

Original application filed July 8, 1919, Serial No. 309,435. Patent No. 1,378,627. Divided and this application filed May 3, 1920. Serial No. 379,320.

To all whom it may concern:

Be it known that I, JESSE A. B. SMITH, a citizen of the United States, residing in Stamford, in the county of Fairfield and 5 State of Connecticut, have invented certain new and useful Improvements in Bill Forms, of which the following is a specification.

This invention relates to work-sheets adapted to be used in typewriting or other 10 type-printing machines, such as a bill-head of a water company. Work-sheets of the type of such bill-heads generally include only a few entries, which hitherto have been placed on two, three or four lines; and often 15 such bills are made upon bill-heads having the name and address of the purchaser or debtor already printed upon them by a so-called addressing machine or other printing device. Such bill-heads in the past have 20 been usually made out with pen and ink, because the placing of a bill-head in a type-writing or other machine and the line-spacing operations absorbed more time than could be profitably devoted to the making 25 out of such bills, since such bills are usually made out by the hundreds or thousands, and the cost of making them out becomes an important item of expense, the bills being usually for small amounts.

30 According to the present invention, the bill-head may be so constructed and proportioned that all items to be printed by the typewriter or other printing machine, at the time of making out the bill, may occupy 35 only a single line, and may be near the bottom of the bill, thus making it possible to write the bill without line-spacing operations. Since line-spacing is unnecessary, the devices for holding the bill while it is being 40 typed or printed may be so constructed as to greatly facilitate the insertion of the bill, thus enabling the typing operation to compete successfully in cost with the present pen-and-ink method of making out the bill.

45 The invention herein disclosed is a division of my co-pending application, Serial No. 309,435, filed July 8, 1919 (now Patent No. 1,378,627, dated May 17, 1921).

Other features and advantages will hereinafter appear.

50 In the accompanying drawing is shown a bill-head of the kind described, with the entries typed thereon.

The bill-head or bill-sheet comprises a 55 body-part 1 having, at the right side there-

of, a lateral extension forming a stub-margin or coupon part 2 detachably connected therewith along a vertical weakened line of detachment, indicated in the drawing as a line of perforations 3. The body-part 1 60 has an upper heading-portion A occupying most of the space thereon, and has a lower narrower item-receiving bottom marginal portion B, which is usually demarcated by means of vertical lines printed thereon, as 65 shown in the drawing, to produce a single transversely-arranged series of spaces 4 to 11, inclusive, which will hereinafter be described. The heading-portion A may have printed thereon an appropriate legend 70 shown in the drawing as: "To Blank Water Co. Dr. Detach coupon and return with check. If you desire receipt return this section also." The detachable marginal coupon part 2 has, as is shown in the drawing, a heading-portion in lateral alignment with the heading-portion A of the body-part 1 and commensurate therewith, and has, at its lower end, a space-providing portion 75 containing a single space 12 in lateral alignment with the series of spaces 4 to 11, inclusive, provided by the lower marginal portion B of the body-part 1.

There is usually printed below the legend 80 a dividing line 13, demarking the heading-portion A from the bottom marginal space-providing portion B and separating the spaces from the legend. Before the bill-head reaches the typist or other machine operator, who is to make the entries upon the 90 bill-head, the bill-head is usually put through a so-called addressing machine, which prints the name of the debtor, the address, and the ledger number of the account, both upon the heading-portion A of 95 the bill-head body 1 and, to the extent desired, upon the extension or coupon stub 2.

At the first aforesaid printing, there is usually also printed a heading for each of the spaces 4 to 12, inclusive, corresponding 100 to the items to be typed therein. When the typist proceeds to type the entries upon the lower marginal portion B of the bill-head 1, the bill-head is inserted in a machine, which may be of the kind described in the aforesaid application, Serial No. 309,435, and typing proceeds, the related items being entered seriatim along a single line, below the headings in the respective spaces.

105 In space 4, under the heading, "Date May 110

1-12," which signifies the date of the bill of the period covered thereby, the typist, making out the bill on the twelfth day of the month, enters the number "12."

5 In space 5, under the heading, "Present reading," the typist types the standing of reading or purchase, herein shown as "123456," indicating the present standing, reckoned from the beginning of the account.

10 In space 6, under the heading of "Date," the typist types "12," the date of that reading, or of the above-noted present standing.

15 In space 7, under the heading "Previous reading", the typist types "102134", taken from a previous entry, indicating the standing at that time.

20 In space 8, the typist types the difference between the two readings under the heading "Consumption", this being "21322", and being the quantity chargeable to the customer.

25 In space 9, under the heading "Total", the typist types the total amount of the bill, "21.32", this being the gross charge for the chargeable quantity.

30 In space 10, the typist types the discount to be deducted, which, being at the rate of 10%, is "2.13".

35 In space 11, under the heading "Net total", the typist types the difference between the total and the discount, viz., "19.19", this being the net charge to the customer.

Finally, in space 12, at the lower end of the coupon part 2 under the heading "Net total", the typist copies the net total "19.19".
35 This finishes the typing, and the bill-head is then ready to be removed from the machine, so that a new one can be typed.

40 It will be noted that so far from forming a handicap to speed, the operation of typing in the manner described actually enhances

the speed of making out the bill, there being no line-spacing operation needed, and there being no handicap of speed in handling the bill-head by the presence of any devices needed for line-spacing.

45 Variations may be resorted to within the scope of the invention, and portions of the improvements may be used without others.

Having thus described my invention, I claim:

50 1. A bill-blank having at its head a printed business heading, and spaces for printing the address of the customer and the ledger number of his account, and having at its foot a series of laterally aligned spaces, each suitably headed to receive numbers indicating one of the following items: the date of a recent meter reading, the state of the meter at that reading, the date of a previous meter reading, the state of the meter at the previous reading, the difference between the readings, and the discount, and two spaces for receiving the net total, the second net total space being formed on the right marginal portion of the bill, said marginal portion being detachable along a perforated line.

55 2. A bill-blank having at its head a space for receiving the unvarying matter common to a series of bills rendered to the same customer, and having along its lower margin a series of laterally aligned spaces, each suitably ruled and headed to receive a single number, and all co-operating to convey to the customer all of the information pertinent to the net amount for which the bill is rendered.

60 JESSE A. B. SMITH.
